UNITED STATES PATENT OFFICE.

JOHN S. TOWNSEND, OF HARVEY, ILLINOIS, ASSIGNOR TO WHITING CORPORATION, OF HARVEY, ILLINOIS, A CORPORATION OF ILLINOIS.

SAND-THROWING HEAD FOR MOLDING MACHINES.

Application filed April 7, 1920. Serial No. 371,800.

To all whom it may concern:

Be it known that I, JOHN S. TOWNSEND, a citizen of the United States, residing at Harvey, in the county of Cook and State of Illinois, have invented a certain new and useful Improvement in Sand-Throwing Heads for Molding Machines, of which the following is a specification.

This invention relates to machines for mechanically projecting sand into a mold box containing a pattern from which casting is to be made, in such manner that hand ramming is not required in the molding operation.

15 The object of the invention is to provide a novel form of sand projecting mechanism which is unusually efficient and satisfactory in use.

The invention consists in means for carrying out the foregoing objects which can be easily made and installed, which is highly efficient in operation, and is not readily liable to get out of order. More particularly the invention consists in feature and 25 details of construction more fully set forth in the specification and claims.

Referring to the drawings in which similar numerals represent the same parts thruout the several views.

30 Figure 1 is a side view partially in section of the mechanism illustrating this invention in its preferred form.

Figure 2 is a side view taken on the irregular line 2—2 of Figure 1.

35 Figure 3 is a reduced size plan view of the mechanism of Figure 1.

In carrying out this invention a pair of continuously moving belts 10 and 12 are provided so located that certain portions 40 10^a and 12^a of the belts are located parallel to each other in proximity to each other and together move downward through a suitable casing 16 open top and bottom. Each belt is provided with a plurality of sand 45 engaging lugs or wings 18 preferably made in the forms shown in the various figures of the drawings and interfitting with corresponding wings on the opposite belt. The parts are so arranged that when sand is de-

50 livered from the hopper 20 over the portions 10^a and 12^a of the belts, the sand will not only pass between the belts but will be engaged by the members 18 and pushed downward between the belts to the point of 55 delivery, into the mold or flask (not shown)

located below the case 16. In practice, the belts are run at such high speed that the wings 18 travel downward faster than the sand moving by gravity only, with the result that the sand is gathered in the spaces 60 formed between adjacent wings 18 on the opposite belts and is delivered from the machine in wads at a greater velocity than that of the sand delivered from the hopper 20.

Broadly speaking, the mounting of belts 65 10 and 12 is not material, but in the preferred form of the device with the belts over the pulleys, there is shown a structure which has certain advantages. In the preferred construction the upper portion of 70 the belt 10 is carried by the pulley 22 mounted upon a shaft 24 journaled in stationary bearings, while the lower end or portion of belt 12 is carried over pulley 26 driven by shaft 28 journaled in fixed bearings. The lower portion of belt 10 passes over a pulley 30 mounted on a shaft 32 journaled in bearing mechanism 34 carried by lever arm 36 journaled to rock about shaft 24. Correspondingly the upper portion 75 of belt 12 is carried on the pulley 38 mounted on a shaft 40 journaled in bearing mechanism 42 carried on a lever arm 44 journaled on shaft 28. There is a lever arm 36 and 44 on each side of the pulleys 80 referred to, as clearly appears from an inspection of Figure 3. Each lever arm 36 is connected to its adjacent lever 44 by a retractile spring 48. The result of the construction described is that the springs 48 85 tend to normally draw pulley 38 and consequently the upper portion of belt 12 yielding toward pulley 22 and to correspondingly draw the lower pulley 30 and the lower portion of belt 10 toward pulley 26. This 90 operation results in the belts 10 and 12 being held in normal position shown. It also provides an opportunity for the belts to separate a substantial distance if a good sized piece of cast iron or other foreign 95 matter happens to be delivered in between the belts and prevents breakage which would otherwise occur.

Shafts 24 and 28 are parallel to each other and one of them, as 24, is driven by power 105 furnished by a source (not shown). The two shafts are connected together thru intermeshing gearing 52 of ordinary construction so arranged that when shaft 24 is rotated all the pulleys and consequently the 110

belts travel in unison with the result that the portions 10^a and 12^a of the belts opposite each other travel downward at uniform speed.

5 Having thus described my invention, what I claim as new and desire to secure by Letters Patent is:

1. In mechanism of the class described, a pair of vertically spaced pulleys, a belt over 10 said pulleys, another pair of vertically spaced pulleys, a belt over said last mentioned pulleys placed face to face with the belt on the first mentioned pulleys, interfitting wings on the opposite belts, means 15 for supplying sand so that it falls in the line occupied by the opposing face portions of said belts, and means for driving said pulleys at such a speed that the belts travel fast enough to gather sand falling by gravity 20 between belts into wads and to deliver it at a speed greater than gravity, and yielding means in the mounting for said pulleys allowing lateral movement of the belts and pulleys to take care of foreign matter 25 passed between the belts.

2. In mechanism of the class described, an upper pulley journaled in fixed bearings, a lower pulley journaled in a bearing carried by an arm on the bearing of the first 30 pulley, a belt over said two pulleys, another belt of substantially the same size facing the first belt and mounted on two pulleys, one above the other, mounted on axes parallel to the axes of the first pulleys, a fixed bearing 35 for the shaft of the lower of said second two pulleys, an arm extending upward from said last mentioned shaft and supporting the bearing of the upper pulley of the second set, and springs connecting the arms 40 controlling the two sets of pulleys, means for rotating said pulleys and for delivering sand above the portions of the belts which are opposite each other, for the purposes set forth.

45 3. In mechanism of the class described, a pair of vertically spaced pulleys, a belt over

said pulleys, another pair of vertically spaced pulleys, a belt over said last mentioned pulleys placed face to face with the belt on the first mentioned pulleys, means 50 for supplying sand so that it falls in the line occupied by the opposing face portions of said belts, and yielding means in the mounting for one of said pulleys allowing lateral movement of the belt which it carries to take 55 care of foreign matter passed between the belts.

4. In mechanism of the class described, a pair of vertically spaced pulleys, a belt over 60 said pulleys, another pair of vertically spaced pulleys, a belt over said last mentioned pulleys placed face to face with the belt on the first mentioned pulleys, means for supplying sand so that it falls in the line occupied by the opposing face portions 65 of said belts, yielding means in the mounting for one of said pulleys allowing lateral movement of the belt which it carries to take care of foreign matter passed between the belts, and means normally forcing said movable belt toward the other belt.

5. In mechanism of the class described, a pair of vertically spaced pulleys, a belt over 70 said pulleys, another pair of vertically spaced pulleys, a belt over said last mentioned pulleys placed face to face with the belt on the first mentioned pulleys, means for supplying sand so that it falls in the line occupied by the opposing face portions of said belts, yielding means in the mounting 75 for one of said pulleys allowing lateral movement of the belt which it carries to take care of foreign matter passed between the belts, and spring means normally forcing said movable belt toward the other belt.

In witness whereof, I have hereunto subscribed my name in the presence of two witnesses.

JOHN S. TOWNSEND.
